(57) **CLAIM**

The ornamental design for a pet treat, as shown and described.

DESCRIPTION

FIG. 1 is a top, front perspective view of a first embodiment of a pet treat according to our design;

FIG. 2 is a front elevational view thereof, with the rear, right and left side elevational views being identical thereto;

FIG. 3 is a top plan view thereof;

FIG. 4 is a bottom plan view thereof;

FIG. 5 is a top, front perspective view of a second embodiment of a pet treat according to our design;

FIG. 6 is a front elevational view thereof, with the rear, right and left side elevational views being identical thereto;

FIG. 7 is a top plan view thereof; and,

FIG. 8 is a bottom plan view thereof.

The stippled shading shown in FIGS. 1, 3, 5 and 7 illustrates a contrasting appearance for a filling portion of the pet treat.
